**DRINKING GLASS FOR SWALLOWING PILLS
AND THE LIKE**

Eric Zanegood, 2908 139th St., Flushing, N.Y.

Filed Mar. 17, 1958, Ser. No. 721,768

1 Claim. (Cl. 128—222)

This invention relates generally to drinking glasses, and more particularly has reference to a device which is used in combination with a basically conventional drinking glass construction, and which when so used facilitates the taking of solid medicaments, such as pills, tablets, capsules, etc.

Many persons have difficulty in swallowing pills or tablets, and this may be particularly true of small children or persons of advanced age. This produces certain problems, with respect to the administering of solid medications to such individuals. Often, the pill is crushed and is taken in a partly or fully dissolved condition. However, this is not always practicable, not only because of the inconvenience and loss of time involved, but also because many pills are quite bitter or unpalatable. This is true, for example, of drugs which are so unpalatable to the taste that they must be enclosed in gelatin capsules that dissolve following swallowing thereof.

It has therefore been proposed to provide means to facilitate the taking of tablets, and the present invention aims to provide an improved device of this general nature. Accordingly, in one embodiment of the invention the device comprises a shallowly recessed, upwardly opening, ledge-like member having a fixed connection to the inner surface of the side wall of the glass, said member being freely perforated in such a manner that when the glass is tilted for drinking of water or another liquid contained therein, the water will flow through the perforations and will wash into one's mouth a pill or pills that were previously deposited in the recessed member. In other words, the recessed member is normally disposed above the level of the water in the glass, so that the pill initially remains dry. Said member is disposed near the lip of the glass, and therefore, when the glass is tilted, the water will run through the perforations and carry the pill into the mouth, so that the pill is swallowed with the water, in such a way that the drinker merely drinks the water in a natural manner to take the pill.

Another object is to provide, in another embodiment of the invention, a device as stated which will be removable so that it can be engaged in any conventional glass, without requiring any modification or redesign of said glass.

Another object is to so form the device, in the last-mentioned form of the invention, that it can be rotated to selected positions within the glass. In this connection, the rotatable adjustment of the device is adapted, in accordance with the invention, to provide a coactive relationship between said device and the glass proper, such that they will provide a reminder as to the next time that a dose of the medicine should be taken. In this arrangement, the device has an index marking at one location thereon, while the glass has a circumferential series of indicia ascending in value from "1" to "12." The index marking, by rotatable adjustment of the device, can thus be registered with any selected numerical indicium so that the user is provided with a reminder as to the next time

2

that a pill must be taken. In other words, in the taking of each pill, the user merely rotates the device to the position indicating the next hour of the day at which the pill is to be taken again.

5 Another object is to provide a device of the character stated which, in both forms of the invention, will include a particular form and relative arrangement of perforations of the recessed member or pill holding element, such as to insure to the maximum extent the proper flow of 10 the liquid through said perforations, in a stream that will immediately carry into the user's mouth the pill that is to be taken.

For further comprehension of the invention, and of the objects and advantages thereof, reference will be had to 15 the following description and accompanying drawings, and to the appended claims in which the various novel features of the invention are more particularly set forth.

In the accompanying drawings forming a material part 20 of this disclosure:

20 Fig. 1 is a view of a device of the character described, and of a drinking glass to which it is integrally connected, the glass being shown partly in side elevation and partly in longitudinal section.

Fig. 2 is a transverse sectional view substantially on 25 line 2—2 of Fig. 1.

Fig. 3 is a sectional view substantially on line 3—3 of Fig. 1.

Fig. 4 is an exploded, fragmentary perspective view of a modified construction.

30 Fig. 5 is a greatly enlarged, fragmentary sectional view longitudinally through the drinking glass shown in Fig. 4, with the device being shown properly positioned therein, said device being shown in section.

Fig. 6 is a sectional view on the same scale as Fig. 5, taken substantially on line 6—6 of Fig. 5.

Fig. 7 is a fragmentary perspective view of the drinking glass with another form of the device positioned therein.

Referring to the drawings in detail, in Figs. 1—3 there is shown a drinking glass 10 which may take any of various forms or sizes. This holds a quantity of water W when in use, or other liquid that one may prefer during the swallowing of a pill A.

In accordance with the invention, a shallowly recessed, segmentally shaped, upwardly opening member or ledge-like element 12 is formed integrally with the side wall of the glass, being connected to said side wall over the full width of said member 12.

The element 12 has an outer edge which is arcuately bowed in a direction inwardly of the drinking glass as 50 shown in Fig. 2. As a result, the recess 13 of the element 12 is obliquely shaped when seen in top plan, with said recess being progressively reduced in width in a direction toward its bottom. In the bottom of the recess, there are formed a plurality of wedge-shaped perforations 14, extending radially inwardly of the glass with their wider 55 ends occurring substantially at the periphery of the glass. Said perforations 14 are of elongated form, extending up the slope of the wall of the member 12 as shown in Fig. 1.

The perforations are of a number and size such as to 60 permit the free passage of the water W therethrough, when the glass is tilted during normal drinking of the water. At the same time, the water is caused to flow in an increased quantity through the base ends of the perforations, as distinguished from the smaller ends thereof 65 located radially inwardly from the side wall of the glass. When the glass is tilted, the pill or tablet A will ordinarily fall against the side wall of the glass, and it will be observed that it is at this location that the maximum flow or stream of the water passes through the perforations.

70 At the same time, there is a more restricted flow through the smaller ends of the perforations, which would be the

upper ends when the glass is tilted for drinking of the water.

By reason of the arrangement illustrated and described, the tablet or pill A is carried into the mouth by the water, during natural drinking of the water, so that the tablet is swallowed along with the water without any effort or conscious action so far as the taker of the pill is concerned. There is thus eliminated the difficulties which have heretofore persisted for some individuals, in connection with the swallowing of pills, tablets, or other solid medicaments.

Of course, the device can be formed with the glass easily, at the time of manufacture of the glass, the construction of Fig. 1 presenting no manufacturing problems.

In the form of the invention shown in Figs. 4-6, there is illustrated a conventional drinking glass 16, with which is associated a device generally designated 18, used to facilitate the taking of pills and similar medications. Glass 16, thus, can be used with any of various devices 18 and vice versa.

The device 18 is formed of a plastic material in the illustrated example, and has a generally annular shape, with a pill-holding element 20 being integrally formed at one location on the circumference of the device. Element 20 is identical to element 12, in shape, size, and in the number and shape of its perforations 22.

However, instead of the glass forming one wall of the recess of the element 20 (as it does in the first form of the invention with element 12), the device 18 includes a pair of integrally connected spring arms 24 each extending through slightly less than 180 degrees of a circle. At the location of the integral connection of said arms, there is defined a wall 25 cooperating with the wall of the member 20 in defining the pill-holding recess.

At opposite sides of the member 20, arms 24 are of a springable nature, and are normally tensioned to spring away from each other into frictional engagement with the inner surface of the side wall of the glass 16. At their free ends, which are spaced closely apart at a location diametrically opposite the member 20, the arms 24 are integrally formed with radially upwardly extending handles 26. These may be pressed together with the thumb and index finger, to move the arms toward each other out of engagement with the wall of the glass.

It can be seen that the construction is such that one may merely insert the thumb and index finger in the glass, and squeeze the handles 26 toward each other, to release the device from engagement with the glass. The device is inserted in the same way, of course, it being understood that when it has been inserted in the glass, the handles are released. The arms 24 will naturally move to a spread condition in engagement with the side wall of the glass.

Referring now to Fig. 7, there is here shown another modification. In this form, the glass 32 has the shape of the glass 16. However, it differs from the glasses previously illustrated and described, in that it has over its full circumference a circumferential series of numerical indicia 34 and of indicia 36 intervening between adjacent numerical indicia to indicate half hours and quarter hours. The numbers of the series 34 ascend in value from "1" to "12."

The device 18^a in this form of the invention is identical to the device 18, with the exception that on one of the arms 24^a, there is an index marking 28 in the form of a radial arrowhead on the top surface of said arm 24^a. This index marking at its small end may merge into a line marking 30 extending over the full width of the outer surface of the arm 24^a, said line marking and index marking 28 facilitating registration of the index with a selected indicium 34 or 36.

Thus, using this form of the invention, one may, after taking a pill, grasp the handles 26^a, moving the same toward each other to release the grip of arms 24^a on glass 32. Then, the device is merely rotatably adjusted within the glass, to locate the index means 28, 30 in registration with a selected, different indicium 34 or 36, to provide a reminder as to the time when the next pill is to be taken.

In all forms of the invention, of course, the functional and structural characteristics of the device are such as to cause the pill or tablet to be carried immediately into the mouth, when the glass is tilted for drinking the water. Further, all forms have the desirable characteristic of permitting manufacture at a comparatively low cost.

While I have illustrated and described the preferred embodiments of my invention, it is to be understood that I do not limit myself to the precise constructions herein disclosed and that various changes and modifications may be made within the scope of the invention as defined in the appended claim.

Having thus described my invention, what I claim as new, and desire to secure by United States Letters Patent is:

The combination, with a drinking glass, of a glass attachment for causing medicament to be carried into the mouth with a liquid that is being drunk from the glass, comprising a ledge member recessed to receive said medicament and adapted to project inwardly from the side wall of the glass, said member having perforations through which the liquid may flow on tilting of the glass, said connection of the member to said wall comprising a ring snugly, removably engaging in the glass, said ring being of the split, springable type and including a pair of integrally connected spring arms spring-tensioned to bear firmly against the inner surface of the wall of the glass, said arms terminating in inwardly directed finger pieces for manipulating the ring, the ring having an index marking on one of said arms and being rotatably adjustable in said glass, the glass having a circumferential series of indicia designating different times of the day when a medicinal dose is to be taken, said marking being selectively locatable in registration with selected indicia, the indicia ascending in numerical value from "1" to "12," the series of indicia and said arms lying in a substantially common plane.
